UNITED STATES PATENT OFFICE.

FRANK H. WEITZ, OF DURYEA, PENNSYLVANIA.

BOBBIN-HOLDER EJECTOR.

1,087,703.

Specification of Letters Patent. Patented Feb. 17, 1914.

Application filed July 31, 1913. Serial No. 782,364.

To all whom it may concern:

Be it known that I, FRANK H. WEITZ, a citizen of the United States, residing at Duryea, in the county of Luzerne and State 5 of Pennsylvania, have invented certain new and useful Improvements in Bobbin-Holder Ejectors; and I do hereby declare the following to be a full, clear, and exact description of the invention, such as will enable 10 others skilled in the art to which it appertains to make and use the same.

This invention relates to a manually operable device for automatically releasing and ejecting the bobbin holder and bobbin from 15 a rotary sewing machine.

The object of the invention is the provision of a device of this character which is quickly and conveniently operable and positive in the performance of its functions.

20 Another object is the provision of a releasing and ejecting device of simple construction and few parts which may be applied to the ordinary construction of rotary sewing machine with but slight variation in 25 the construction of the parts thereof.

In the accompanying drawing, Figure 1 represents a fragmentary view, partly in section, through the base of a rotary sewing machine showing my improvement applied 30 thereto. Fig. 2 represents a fragmentary side elevation, and, Fig. 3 represents a longitudinal sectional view through the main shaft of the machine, the bobbin holder and bobbin.

35 Referring to the drawings, wherein similar reference characters designate corresponding parts, throughout the several views, 5 indicates the main shaft supported below the base 6, over which are mounted 40 the usual adjuncts of the ordinary rotary sewing machine. The shaft 5 is preferably formed in two parts, the part carrying the crank 7 being threaded at the inner end and having a flange 8 at the inner end of the 45 threaded portion. The inner portion of the other part of the shaft is enlarged at 9 and threaded at the inner end to receive the threads of the first part. The second part is provided with a longitudinal bore 10 extending 50 in alinement with the bore of the sleeve 10^a integral with the rotary hook or shuttle 11^a, and said bore 10 is enlarged at 11 at the inner end, and the wall of the enlarged portion of the bore is slotted at 12. A plunger 55 13 is positioned in the bores 10 and 11, and

the end 13^a thereof is headed to provide an abutment for a spring 14, the normal tendency of which is to withdraw the plunger 13. A channeled collar 15 is slidably mounted over the enlarged portion of the shaft 60 and carries a pin 16 which is secured at its inner end through the head 13^a and is adapted to work longitudinally through the slot 12. A shifting rod 17 is slidable longitudinally through the depending flanges 18, ordinarily formed integrally with the base 6, which latter is in this instance provided with a slot 19 through which projects the operating lever or handle 20 fixed to the shifting rod 17. One end of an arm 21 is split and suitably fixed over the shifting rod 17, and yoked at the opposite end to be loosely received within the channel of the collar 15. One end of the shifting rod 17 is beveled on 70 its under surface to provide a cam face 22. A bobbin holder release lever 23 is pivoted at 24 to the base 6 or part of the frame and is provided with a depending lug 25, at one end, which is normally held against the bobbin holder for securing the latter in position 75 by a spring 26. The opposite end of the lever 23 is engaged against the beveled face 22 of the shifting rod.

The parts herein described which comprise the bobbin holder ejector do not interfere with the usual operation of the sewing machine, and the shifting rod 17 and plunger 13 are normally held retracted by the tension of the spring 14, as will be understood.

To operate the parts to release and eject the bobbin holder, the handle or lever 20 is shifted by the operator, moving the shifting rod 17 longitudinally, causing the release lever 23 to be rocked sufficiently to disengage the lug 25 from the bobbin holder. Simultaneously, the movement of the rod 17 is imparted to the plunger 13 through the medium of the arm 21 and collar 15. As the plunger moves outwardly through the bore of the sleeve 10^a, it engages the end of the stem 27 secured in the usual way to the holder 28 and ejects the latter together with the bobbin 29 removably secured therein.

To replace the bobbin and holder in position within the hook, the free end of the bobbin release lever 23, which is preferably curved outwardly to provide a suitable grip, is partially lifted and the parts placed in position, after which the lever is released.

and the tension of the spring 26 moves the lug 25 thereof into locking engagement against the bobbin holder.

What I claim is:—

- 5 1. A bobbin and bobbin holder ejector comprising a bobbin holder release lever, means for depressing one end of said release lever to release the bobbin holder, and an ejector plunger operably connected with 10 said depressing means.
2. A bobbin and bobbin holder ejector comprising a bobbin holder release lever, means for depressing one end of said lever to release the bobbin holder, an ejector plunger, and a connection for moving said depressing means and said ejector plunger longitudinally simultaneously.
- 15 3. In a sewing machine, the combination

with a hollow main shaft and rotary hook, of a bobbin holder release lever, means for depressing one end of said lever for releasing the bobbin holder, an ejector plunger positioned through said main shaft, and a connection between said depressing means and said ejector plunger permitting the ejector 25 plunger to rotate independently of said means, whereby said bobbin holder release lever and ejector plunger are moved simultaneously.

In testimony whereof I have signed my name to this specification in the presence of two subscribing witnesses.

FRANK H. WEITZ.
